UNITED STATES PATENT OFFICE.

WILLIAM D. YOUNG, OF PITTSBURG, ASSIGNOR TO CHARLES L. FITZHUGH,
OF ALLEGHENY CITY, PENNSYLVANIA.

KNIFE FOR NAIL-CUTTING MACHINES.

SPECIFICATION forming part of Letters Patent No. 355,113, dated December 28, 1886.

Application filed November 17, 1886. Serial No. 219,118. (No model.)

To all whom it may concern:

Be it known that I, WILLIAM D. YOUNG, of Pittsburgh, in the county of Allegheny and State of Pennsylvania, have invented a new and useful Improvement in Knives for Nail-Cutting Machines, and I do hereby declare the following to be a full, clear, and exact description thereof.

In the manufacture of cut chisel-pointed 10 nails of steel the ordinary nail-cutting machine has been used with knives which cut a headed and pointed blank.

In Figure 1 of the accompanying drawings the form of the cutting-edges of the knives 15 will be seen, the said view being a plan of the knives when in conjunction. Here *a* is the moving knife, and *b* the fixed or bed knife, the former moving nearly at a right angle to the latter, and sufficiently beyond the upper edge of 20 the same to completely sever the nail-blank from the plate from which it is cut and to deliver it within range of the gripping-dies which hold it while being headed. The edges 2, which form the tapered sides of the nails, extend at 25 a proper angle for that purpose, and at the ends they are provided with short bevels 3 and 4, for forming the points and heads of the blanks. The bevels 3 run inwardly and the bevels 4 outwardly, and at each stroke of the 30 knife *a* one side of the nail-blank is formed, which will be the counterpart in shape of the cutting-edge of the knife *b*.

In Fig. 2 of the drawings the operation of 35 the knives is clearly illustrated. Here *c* is the nail-plate, which is placed between the knives *a* and *b*, and the end or scrap 5 is cut off to form the outer edge of the first nail-blank, 6, as shown. Then the plate is reversed in the usual way and inserted between the knives, 40 which at their second cut sever the first nail-blank, 6, and form the outer edge of the next nail-blank.

As heretofore made the lower edge of the 45 knife *a* is straight, and in operating upon steel plate the action of the straight edge upon the stiff hard stock is apt to produce a nail with the point turned slightly to one side, as illustrated in the side view of the nail-blank shown by Fig. 3. This point is always on the upper 50 side, the effect of the pressure of the knife *a* upon the nail-plate, which is partially sepa-

rated by the bevel 3 of the knife *b*, being to turn up the point of the nail as it is severed from the plate. This result produces a very serious defect in the nail, for the reason that 55 a very slight deflection or turning of the point will cause the nail to drive sidewise and frequently break, and thus destroy its usefulness.

The object of my invention is to overcome this defect by an improved construction of the 60 knives used for cutting steel bevel-pointed nails.

To enable others skilled in the art to make and use my invention, I will now describe it by reference to the accompanying drawings, 65 in which—

Fig. 1 is a plan view of the cutting-knives of a nail-machine for cutting bevel-pointed nails. Fig. 2 is a plan view of a nail-plate, illustrating the operation of the knives. Fig. 3 70 is a view of the nail-plate, made with a straight-edged knife of the old form. Fig. 4 is a side view of the old form of moving knife. Fig. 5 is a side view of my improved form of moving knife. Figs. 6 and 7 are side and edge 75 views of the nail made by my improved knives.

Like symbols of reference indicate like parts in each.

As before stated, the effect of the straight-edged knife shown in Fig. 4 is to produce a 80 nail like that shown in Fig. 3, in which the point is turned or curved sidewise. I find that by forming a slight projection with a beveled face, which acts upon the upper side of the point of the nail-blank upon the outer 85 edge of the moving knife *a*, as indicated in Fig. 5 at *d*, the upper side of the point will be compressed, so as to form a bevel thereon equal to the bevel which is formed on the under side of the blank by the supporting action of 90 the bevel 3 of the bed-die *b*, so that the defect heretofore existing in steel bevel-pointed nails, produced by the ordinary straight-faced moving knife, will be completely overcome and 95 cured by the addition of the projection *d*, and the nail produced will not only be beveled upon the cut sides, but also upon the straight sides of the point, thereby giving a much better driving-nail than is had in the simple bevel-point.

In the use of my improved moving knife, the point *d* encounters the nail-plate before 100

any other portion of the knife, and acts with a compressing as well as a shearing effect upon the sharp point of the blank, so as to compress and bevel it, while the body of the nail 5 is still attached to and supported by the plate.

Nails produced by my improved moving knife not only drive straight, but much more easily than the ordinary bevel-pointed nail, and are practically perfect.

10 What I claim as my invention, and desire to secure by Letters Patent, is--

1. A moving knife for machines for cutting bevel-pointed nails having a beveled projection at the point end, substantially as and for 15 the purposes described.

2. The combination, in a machine for cutting nails, of a moving knife with a bed-knife for forming a bevel point on the nail-blank, the point end of the moving knife being provided with a beveled projection, substantially as and 20 for the purposes described.

In testimony whereof I have hereunto set my hand this 6th day of November, A.D.1886.

WILLIAM D. YOUNG.
